UNITED STATES PATENT OFFICE.

SOREN JENSEN, OF LOS ANGELES, CALIFORNIA.

PENCIL-SHARPENER.

1,375,295.

Specification of Letters Patent. Patented Apr. 19, 1921.

Application filed August 5, 1920. Serial No. 401,499.

To all whom it may concern:

Be it known that I, SOREN JENSEN, a citizen of the United States, residing at Los Angeles, in the county of Los Angeles and 5 State of California, have invented new and useful Improvements in Pencil-Sharpener, of which the following is a specification.

This invention relates to pencil sharpeners of the type adapted to be mounted upon 10 a pencil and of the general class of pencil sharpeners such as set forth in my prior U. S. Letters Patent No. 965,907, granted August 2, 1910, and 1,130,294, granted March 2, 1915,

It is the object of the present invention to 15 provide an improved pencil sharpener of this type which will form a pencil point guard when the pencil is not in use, and which may be shoved up upon the pencil to uncover the point thereof when the pencil 20 is to be used. When the pencil is to be sharpened it is only necessary to slide the sharpener down along the pencil, and it is not necessary to remove the sharpener from the pencil when the sharpener is to be 25 brought into operative position.

The invention will be readily understood from the following description of the accompanying drawings, in which—

Figure 1 is a perspective view showing 30 the pencil sharpener upon a pencil in position to permit use of the pencil.

Fig. 2 is a similar view showing the pencil sharpener moved down to form a point guard for the pencil.

Fig. 3 is a similar view showing the sharpener in operative position for sharpening the pencil point.

Fig. 4 is a top plan view of the pencil sharpener.

Fig. 5 is a side elevation of the same.

Fig. 6 is a longitudinal section on the line 6—6 of Fig. 4.

Fig. 7 is a bottom plan view of the pencil sharpener.

Fig. 8 is an end view of the same.

Fig. 9 is a perspective view of the cutting blade.

The sharpener is shown mounted upon the pencil 1, the sharpener consisting of a substantially tubular structure 2 formed of sheet metal. The side edges of the sheet metal blank are brought substantially together so as to form the longitudinal slot 3, and the top of the tubular structure is 55 provided with a slot 4 adjacent the forward end thereof, which at its rear end termi-

nates in a lip 5 projecting forwardly into slot 4. This lip is provided with an upturned front end 6 and the arrangement of the lip provides a spring member adapted 60 to removably retain the cutting blade of the sharpener in position.

In front of slot 4 the tubular structure forms a cross strip 7 beneath which the cutting blade extends so as to rest upon the 65 portions 8 of the tubular structure at the sides of slot 4. The tubular structure beyond the cross strip 7 is recessed inwardly from the end of said structure as shown at 9. The portion of said tubular structure at 70 one side of the recess 9 forms a supporting extension 10 beneath which extends the cutting blade which is positioned beneath cross strip 7 and upon the shoulders 8.

The opposite side of the recess 9 is engaged by a lateral continuation 11 extending from the opposite side edge of the blank forming the tubular structure, said lateral extension being bent around and over the edge of the tubular structure at the recess 80 9. This portion 11 of the tubular structure is, preferably, tapered toward its forward end, as clearly shown in Fig. 8, so as to terminate in the opening 12 through which the point of the pencil extends when the 85 pencil is in position for use. The portion of the tubular structure forming the supporting extension 10 is, preferably, reversely bent beneath the same, as shown at 13 in Fig. 8, in order to provide the longitudinal 90 groove 14 for the cutting blade. The cutting blade is mounted with its cutting edge 15 extending along recess 9 in position to lie adjacent the end of the pencil projected through opening 12.

The blade comprises a shank portion 16 underlying cross strip 7 and a rear extension 17 resting upon shoulders 8. The rear end of this extension is provided with a notch 18 adapted to engage the upturned end 6 100 of the spring retaining lip 5. The cutting blade projects forwardly from shank 16 so as to be received in the groove 14 and is, preferably, downwardly bent relative to said shank so as to conform to the desired taper 105 arranged to be provided at the pencil point.

It will be understood that the cutting blade is retained in position by spring lip 5, and when it is desired to insert a new blade it is only necessary to bend the lip upwardly 110 so as to disengage the same from the extension 17 of the cutter, and the latter may

then be readily removed by withdrawing it from groove 14 and from beneath cross strip 7.

In operation the sharpener is placed upon the end of a pencil, the sides of the blank forming the tubular structure of the sharpener being brought toward one another at the slot 3 to form a clamp adapted to engage the pencil. When the pencil is not in use 10 the sharpener is slid downwardly thereon so as to cover the point and form a protector therefor, as clearly shown in Fig. 2. When the pencil is to be used the sharpener is slid along the pencil so as to uncover the point, 15 as shown in Fig. 1.

When it is desired to sharpen the pencil it is only necessary to hold the sharpener against rotation by one hand and rotate the pencil relative to the sharpener by the other hand so as to cause the blade of the cutter to impinge with a cutting action against the 20 wood at the pencil end.

Various changes may be made without departing from the spirit of the invention as 25 claimed.

What is claimed is:

1. In a pencil sharpener, a tubular member having a tapered slotted forward end, a spring tongue projecting into the slot in 30 said forward end, a plate positioned on the forward portion of said tubular member and retained in place by said spring tongue, an inclined finger projecting downwardly from said plate and positioned at one side of the 35 slot in the tubular member and said finger being beveled on one side to form a cutting edge.

2. A pencil sharpener including a tubular structure positioned upon a pencil, a cutter at the end of said tubular structure and comprising a plate and an inclined finger projecting downwardly from said plate, said finger having a cutting edge extending lengthwise of said pencil, said tubular structure and pencil being arranged for relative 45 sliding movement in order to project or retract the pencil point with relation to the end of said sharpener.

3. A pencil sharpener including a tubular structure having an end recess, a slot spaced 50 from said recess to form a cross strip, and a removable cutter inserted beneath said cross strip and positioned at said end recess which removable cutter comprises a plate, an inclined finger formed integral with and projecting downwardly from said plate, one side of which finger is beveled to form a cutting edge.

4. A pencil sharpener including a tubular structure having an end recess, a slot spaced 60 from said recess to form a cross strip, a removable cutter inserted beneath said cross strip and positioned at said end recess, said cutter comprising a notched plate and an inclined finger projecting downwardly therefrom, one side of which finger is beveled to 65 form a cutting edge, and a spring lip projecting into said slot and arranged to engage in the notch in said plate for retaining the same in position.

In testimony whereof I have signed my name to this specification.

SOREN JENSEN.
